UNITED STATES PATENT OFFICE.

JOHN W. ACHARD, OF PHILADELPHIA, PENNSYLVANIA.

END-CELL SWITCH.

1,140,322.

Specification of Letters Patent. Patented May 18, 1915.

Application filed March 9, 1911. Serial No. 613,255.

To all whom it may concern:

Be it known that I, JOHN W. ACHARD, a citizen of the United States, and a resident of Philadelphia, county of Philadelphia, 5 State of Pennsylvania, have invented certain new and useful Improvements in End-Cell Switches, of which the following is a specification.

My invention relates to switches in which 10 a movable contacting member coöperates with a series of contacts connected to intermediate points in a series of storage battery cells, and the object of my invention is to provide an improved method of mounting 15 the auxiliary resistance interposed between the traveling member and the contact points.

My invention will be more clearly understood by reference to the following description taken in connection with the accompanying drawings, in which—

Figure 1 is a diagrammatic view of an end cell switch embodying features of my invention, Fig. 2 is a section of one of the contact points along the line A A of Fig. 1 25 drawn to an enlarged scale. Fig. 3 is a section of the same contact point by a plane at right angles to the line A A.

Referring to Fig. 1, B is a storage battery connected at one end to conductor 1 of the 30 load circuit. Several points near the other end of the battery are connected to several contact points 2, 3, 4, 5 and 6 of an end cell switch. The longitudinal bar C of this switch is connected to the other conductor 7 of the load circuit. A traveling brush D serves to connect the bar C with any one of 35 the points 2 to 6, according to its position. The position of the brush D is controlled by a screw E mounted in bearings and rotated 40 by means of a handle F. Each of the switch points, for example point 3, consists of a portion 8 of conducting metal, such as copper upon which the brush D rests when in full contact with the switch point, and a 45 portion 9 of comparatively high resistance material, such as carbon, firmly connected to the portion 8 but projecting on either side thereof, so as to form auxiliary high resistance contacts when the traveling brush D is 50 passing from point to point. The brush D is shown in an intermediate position between the points 4 and 5, making contact with the auxiliary resistances between these two points, but out of contact with the metallic portion 55 of these points. In this position there is a circuit of comparatively high resistance

across the terminals of the cell, to which points 4 and 5 are connected, through which a certain amount of current will flow while the brush is traveling between these points. 60 This current may be limited to any desired value by proper design of these auxiliary resistances.

In Fig. 2 is shown one method of combining the auxiliary carbon resistance with the metallic portion of the switch point. This metallic portion is forked at one end to receive the carbon block 9, the upper and lower portions of the fork being indicated at 8^a and 8^b, respectively. Firm and rigid contact between the metallic portion and the carbon is secured by means of the bolts 10.

One of the advantages of this method of construction over that in which the auxiliary resistance is carried by the brush lies in the 75 fact that with my improved method of construction, the auxiliary resistance may be varied at different points in the switch. In connecting an end cell switch to the end cells of a storage battery, it is sometimes desirable to include different numbers of cells 80 between adjacent points at different parts of the switch. Thus at the extreme end of the battery, it may be desirable to connect two cells between adjacent points, whereas near 85 the other end of the series of end cells, in order to provide for a closer adjustment of the floating point, it may be desirable to connect only one cell between adjacent 90 points. This method of connection is illustrated in Fig. 1. The proper design of resistance for bridging across the terminals of a single cell will not be the best design for 95 bridging across two cells. With the improved construction of my invention, it is 100 possible to vary the design of these auxiliary resistances to correspond with the varying number of cells connected between adjacent points, whereas with the resistance carried by the brush the design cannot be changed 105 for different parts of the switch. The improvement described above also permits a more rigid construction of these auxiliary resistances, and permits the omission of the dead points heretofore used between adjacent contact points for supporting the brush when in an intermediate position between the two contacts.

An additional advantage lies in the gradual introduction of resistance as the brush 110 recedes from one of the main contacts, and the gradual reduction of resistance as the

brush approaches a contact. This result might be secured by mounting the auxiliary high resistance contact on the brush itself, but in this case the same auxiliary contact is subjected to the excessive heating effect of the current throughout the entire travel of the brush, whereas with the arrangement of my invention each auxiliary contact is used only once, as the brush travels from one end of the switch to the other, and the heating effect is thus divided among a number of contacts.

Having described my invention what I claim and desire to secure by Letters Patent is—

1. In a multiple point switch including a series of stationary main contact terminals spaced apart and coöperating therewith a traveling brush narrower than the space between said terminals, the combination with said main terminals of auxiliary contacts consisting of conducting blocks of comparatively high resistance rigidly attached to and in electrical contact with said main terminals, each block extending across the corresponding terminal beneath the contact surface thereof, and projecting on either side, the projections being brought flush with said main contact surface, so as to form

high resistance auxiliary contacts for the brush between the main contact terminals, substantially as described.

2. In a multiple point switch, a main contact terminal forked by a slot beneath the contact surface in combination with a conducting block of comparatively high resistance rigidly fastened in the fork, and extending on either side thereof, said block being notched to receive the fork, substantially as described.

3. In combination an end cell switch having a series of stationary contacts spaced apart, a storage battery divided into groups containing different numbers of cells, connections between the adjacent switch contacts and the adjacent groups and stationary conducting members of comparatively high resistance arranged between the contacts and respectively electrically connected thereto, said members differing in resistance between themselves to correspond with the different numbers of cells in said groups.

In testimony whereof I have hereunto signed my name.

JOHN W. ACHARD.
